FIG. 2

UNITED STATES PATENT OFFICE

2,551,434

SUBSURFACE PUMP FOR FLOODING OPERATIONS

James Earle Gray and Eldon Allen Davenport,
Centralia, Ill., assignors to Shell Development
Company, San Francisco, Calif., a corporation
of Delaware

Application April 5, 1949, Serial No. 85,524

1 Claim. (Cl. 166—1)

1

This invention relates to well apparatus for use in the secondary recovery of hydrocarbon fluids and pertains more particularly to a subsurface well pump adapted to be positioned in a well borehole for pumping fluid from an upper fluid-bearing formation into a lower hydrocarbon-bearing formation, where the well borehole passes through both formations.

Within the past years, it has become common practice in the production of hydrocarbon fluids to apply secondary recovery methods such as water flooding to an oil reservoir after it has been substantially depleted. The water introduced into the producing reservoir through an injector well cleanses the producing formation of its oil and moves the oil toward nearby producing oil wells.

The usual practice in such cases is to obtain the water for injection into the hydrocarbon-bearing formation from a suitable source of supply on the surface, and to pump it through a well borehole and into said formation by a suitable pump located on the surface.

In many oil pools, water-bearing formations are existent above or below producing or oil or gas bearing formations. Water from an upper formation may be utilized in water-flooding the oil or gas formation through a common bore provided that the volume and pressure of the water are great enough. By employing this water, it will be evident that the expense of obtaining and piping necessary water from extraneous sources may be eliminated.

While water from a water-bearing formation may be obtained in quantities sufficient to carry out water flooding operations in a particular location, the formation water may be under such slight pressure that it cannot be forced into an oil-bearing layer unless auxiliary pressure is supplied by a suitable pumping apparatus.

It is, therefore, a primary object of the present invention to provide a pumping apparatus adapted to be positioned in a well borehole for pumping fluid through said borehole from one strata to another.

It is also an object of this invention to provide a well pump for pumping predetermined quantities of fluid from an upper water-bearing formation into a lower fluid-bearing formation through a common well borehole to drive the fluid in the lower formation toward a region from which it may be withdrawn to the surface.

A further object of this invention is to provide a well pump for pumping well fluid through a common borehole from one strata to another, said

pump being adapted to be run into a well borehole and reciprocated therein by equipment commonly used in petroleum production.

5 A further object of this invention is to provide a pumping apparatus of the character indicated, said apparatus being simple and sturdy in construction, and comparatively inexpensive to manufacture, install and operate.

10 Other objects and advantages of the invention will become apparent from the following detailed description taken with reference to the drawing, wherein:

15 Figure 1 is a longitudinal view, partly in cross-section of the present pumping apparatus positioned within a well borehole.

Figure 2 is a cross-sectional view taken along the line 2—2 in Figure 1.

20 A typical well installation is illustrated in Figure 1 wherein a borehole 10 is lined with a casing 11 closed at the top by a casing head 12. The annular space 13 between the borehole wall 10 and casing 11 is normally filled with cement, at least near the top and bottom of said casing as shown at 14 and 15 respectively adjacent any 25 water-bearing formations 16, as shown at 17. Suspended from slips 18 within said casing 11 is a string of pipe or tubing 19 which is closed at the top in preferably a fluid-tight manner by a suitable closure and lubricator means 20.

30 A sucker rod string 21 depends within said tubing string 19 and is reciprocated therein by the oscillating motion of a walking beam 22, which is driven by a pitman 23, crank 24 and prime mover 25.

35 Secured to the lower end of the tubing string 19, by a coupling 26, is a well pump 27, which comprises a pump barrel 28 having a standing valve assembly in the lower end thereof. This assembly consists of a transverse plate 29 having 40 a valve seat 30 therein, an upwardly opening ball valve 31 and a perforate baffle plate 32.

Affixed to the lower end of the string of sucker rods 21 and mounted for sliding movement within the pump barrel 28 is a hollow pump plunger 33 equipped with a traveling valve assembly. The plunger 33 is provided with a passage or orifice 34 opening to the space within the pump barrel 28 below the plunger and forming a valve seat for an upwardly opening ball valve 35. The 45 plunger 33 is also equipped with outlet ports 36 in communication with the space inside the pump barrel above the plunger. The lower end of the pump barrel 28 may be closed by a transverse plate member 37.

50 The plate member or coupling 37 may be

threaded to receive and secure a barrel extension or tubular member 38 coaxial with said pump barrel 28 having perforations or fluid ports 39 therethrough. One or more similar perforations 40 through the wall of the pump barrel 28, near its upper end, serve as discharge ports from the pump.

Coaxially surrounding the pump barrel 28 and spaced therefrom is a tubular member 41 extending from a point above the discharge ports 40 to a point below the perforations 39 in member 38. The ends of said member 41 are swaged so as to be closed against the pump barrel 28 and barrel extension 38 as at 42 and 43, respectively, said closure being made fluid-tight in any suitable manner, as by welding. Thus, the surrounding tubular member 41 forms an annular space 44 between said member 41 and the pump barrel 28, said annular space 44 forming conduit means between fluid ports 39 and 40.

The pump is provided with one or more fluid intake ports 45 which are formed of short tubular pieces 46 extending in a fluid-tight manner through the walls of said barrel 28 and surrounding tubular member 41, whereby the space within the pump barrel 28 below the standing valve 31 is in communication with the space outside the tubular member 41.

Carried on the outside of the pump below the inlet ports 45 thereof, either on the tubular member 41 or on the barrel extension 38, as shown, is a suitable packer means 47. Since the structure and operation of the packer means form no part of this invention and are well known in the art, they will not be described here in detail.

In flooding operations, the present pump is secured to the lower end of the tubing string 19 and lowered into a well borehole or well casing 11 to a position between an upper water-bearing sand 16 and a lower oil-bearing sand 48. Previously, the casing 11 and the surrounding layer of cement 17 adjacent the water-bearing layer 16 is perforated at 50 by any suitable device such as a casing perforating gun. The packer 47 carried by the pump 27, or tubing 38 depending therefrom, is then expanded to seal off the annular space 49 between the pump 27 and the casing 11. Water from the water-bearing sand 16 flows through the perforations 50 in the cement sheath 17 and casing 11 to fill said annular space 49.

In the operation of the pump 27, the reciprocating motion of the sucker rod string 21 causes the hollow plunger 33 to move slidingly up and down within the pump barrel 28. On the up-stroke of the plunger 33, water is drawn in the pump intake 45, and through the perforate plates 29 and 32 into the pump barrel 28 above the open standing valve 30. At the same time fluid standing above the closed traveling valve 35 is forced up the barrel 28, out the perforations 40, down the annular conduit 41 and through 39 and tu-

bular member 38 to be discharged into the well casing 11 below the packer 47 and thence into the oil-bearing formation 48.

On the downstroke of the plunger 33, the standing valve 31 closes and the fluid in the pump barrel 28 between the standing valve 31 and traveling valve 35 is forced through perforations 34 and 36 into the pump barrel 28 above said traveling valve 35. From the above-described operation it may be seen that all fluid flowing from the water-bearing sand 16 and accumulating between the casing 11 and pump 27 above the packer 47, may be forced under any desired pump pressure into the oil-bearing sand 48 to drive the oil therein to adjacent oil-producing wells. The flow of fluid from the water-bearing sand 16 to the oil-bearing sand 48 may be readily controlled by the rate at which the pump 27 is reciprocated.

Although the operation of the present pumping system has been described with reference to an upper water layer and a lower petroleum producing layer, it is understood that with suitable modifications it can equally well and without departing from the spirit of the invention be applied to any other geometrical configuration of formation layers.

We claim as our invention:

A well pump adapted to be installed on a tubular string member in a well to apply auxiliary pressure to a fluid being transferred from an upper relatively low-pressure formation to a lower relatively high-pressure formation, said pump comprising a pump barrel co-axial with said tubular string member, said tubular string member having upper and lower closure means above and below said pump barrel, a standing valve in said barrel, a traveling valve mounted for reciprocation in said barrel above said standing valve, a cylindrical housing closed at the top and bottom disposed around said barrel in spaced co-axial relationship therewith, port means through the walls of said barrel above the traveling valve opening to the space within said housing, port means in said tubular member below said lower closure means opening to the space within said housing, and conduit means extending radially through said housing, said conduit means opening at their outer ends to the space outside said housing and at their inner ends to said barrel below said standing valve and above said lower closure means.
